UNITED STATES PATENT OFFICE.

WILLIAM H. MCKISSICK, OF TAFT, CALIFORNIA.

DEVICE FOR HOLDING WELL-TUBINGS.

1,147,108.

Specification of Letters Patent. Patented July 20, 1915.

Application filed March 12, 1913, Serial No. 753,819. Renewed April 14, 1915. Serial No. 21,454.

To all whom it may concern:

Be it known that I, WILLIAM H. MCKISSICK, a citizen of the United States, residing at Taft, in the county of Kern and State of California, have invented certain new and useful Improvements in Devices for Holding Well-Tubings, of which the following is a specification, reference being had to the accompanying drawings.

10 This invention relates to new and useful improvements in packers for oil wells and the like and the primary object of the invention is to provide a device of this character which will securely prevent the tubing from sliding or dropping downwardly into the well.

A further object of the invention resides in providing a sleeve like body member with spring held slips or friction jaws carried thereon and a still further object resides in providing beveled faces on the sleeve-like body, with which coöperate the beveled inner faces of the slips for forcing the latter outwardly, when the body drops downwardly.

25 A still further object of the invention resides in providing a device which is extremely simple and durable in construction, inexpensive to manufacture and one which will be very efficient and useful in operation.

With these and other objects in view, the invention consists in the novel features of construction, combination and arrangement of parts as will be hereinafter referred to 35 and more particularly pointed out in the specification and claims.

In the accompanying drawing forming a part of this application, Figure 1 is a side elevation of my device. Fig. 2 is a vertical 40 section therethrough as seen on line 2-2, of Fig. 1, with parts in elevation. Fig. 3 is a horizontal section therethrough as seen on line 3-3, of Fig. 1. Fig. 4 is a similar view as seen on line 4-4 Fig. 1; and Fig. 5 45 is a perspective view partly in section of one of the slips removed.

In describing my invention, I shall refer to the drawing in which similar reference characters designate corresponding parts 50 throughout the several views and in which 1 indicates a pipe or tubing which is disposed in an opening 2, formed in the ground and leading to a well therebelow. In order to hold the tubing in position in the casing of 55 the opening 2, to prevent the same from

dropping downwardly, while an additional tubing section is being secured thereto, I provide my packer or the like, which consists of a sleeve-like body member 3, loosely applied to the tubing 1, said body having 60 the bore at its upper end slightly enlarged and threaded, as shown at 4. Also applied to the tubing 1; and threaded into engagement with the threaded end 4, of the body 3, is a sleeve member 5 which is provided at 65 diametrically opposite points therein with the vertical slots 6, the lower ends of said slots terminating in the angular or lateral notches 7.

Applied to the tubing 1, and secured 70 thereto, through the medium of the bolts 8, is a band or ring 9, the shanks of these bolts being disposed through the vertical slots 6 in the sleeve 5, thereby permitting the heads of said bolts to project beyond the latter. 75 The body 3, with the sleeve member 5 may, therefore, be said to have connection with the tube 1, to be moved upwardly and downwardly with the latter and secured to the body 3 and extending longitudinally thereof, 80 at diametrically opposite points thereon, are the friction springs 10. These friction springs are adapted to contact with the walls of the well casing to prevent rotation of the body member and parts carried 85 thereby.

The sleeve-like body member 3 is also provided at diametrically opposite points thereon and alternating the springs 10, with the inwardly beveled faces 11 and adapted to 90 be applied to these beveled faces are the slips or friction jaws 12, the inner faces of which are beveled outwardly toward their lower ends coincident to the inclination of the faces 11, whereby when said slips are 95 properly applied to the body 3, the same complete the formation of said body. Also applied to the tube 1, below the body 3, is a plate 13, to which is applied a collar or the like 14 which also encircles the tube 1 and 100 loosely disposed through openings in the plate 13, at diametrically opposite points thereon, are the bolts 15, the threaded free ends of which are engaged with the lower ends of the slips or friction jaws 12. Encircling these bolts 15, between the plate 13 and the under faces of the slips or friction jaws 12, are the coil springs 16, and as this plate 13 is adapted to be applied to the tube 1, at a point immediately above a shoulder 110

17 formed on said tube, the tendency of said springs will be to force the slips 12 upwardly.

After my attachment is applied to the 5 tube 1, the latter is turned until the shanks of the bolts 8 register with the vertical slots 6, whereupon said tube is allowed to drop downwardly through the opening 2. As the latter is dropped downwardly, carrying 10 therewith the sleeve member 5 and sleeve-like body 3, and the slips 12 sliding along the beveled faces 11 of the body member 3 will be forced outwardly to frictionally engage 15 the walls of the casing, thereby securing the tube against downward movement. The friction springs 10 on the body member 3 will prevent the rotation of the latter and parts carried thereby as the device is dropped downwardly.

20 From the foregoing it will be seen that I have provided a device which is extremely simple and durable in construction, inexpensive to manufacture and one which will be very efficient and useful in operation and 25 while I have particularly described the elements best adapted to perform the functions set forth, it is obvious that various changes in form, proportion and in the minor details of construction may be resorted to without departing from the spirit or sacrificing any of the principles of the invention.

In practice, it is desirable to provide a water course on the outer faces of the members 12 to permit the water to travel there- 30 through as the device is lowered in the well.

Having thus described this invention, what I claim is:—

1. In a device of the class described, the combination with a tubing adapted for use 40 in connection with a well; of a sleeve-like body member loosely applied thereto, said body member being provided at diametrically opposite points thereon with inwardly beveled faces, a sleeve member applied to 45 the tubing and removably engaged with the upper end of said body member, said sleeve member being provided with vertical slots at diametrically opposite points thereon, said slots terminating at their lower ends in lat- 50 erally extending and outwardly flaring

notches, means engaged with said tubing and extending through the slots of said sleeve member to afford a substantial connection between the tubing and sleeve member, a plate loosely applied to said tubing below 55 the body member, bolts loosely disposed through said plate, a pair of slips secured at their lower ends to the upper ends of said bolts and applied to the beveled faces of said body member, and spring members encir- 60 clining said bolts between the plate and lower ends of said slips.

2. In a device of the class described, the combination with a tubing adapted for use in connection with a well; of a sleeve-like 65 body member loosely applied thereto, said member being provided at diametrically opposite points thereon with inwardly beveled faces, a sleeve member also applied to said tubing and removably engaged with the 70 upper end of said body member, said sleeve member being provided at diametrically opposite points thereon with vertical slots which terminate in laterally extending and outwardly flaring notches, means engaged 75 with said tubing and extending through the slots of said sleeve member to afford a sliding connection between the tubing and said body member, spring controlled slips applied to the beveled faces of said body mem- 80 ber and adapted to engage the wall of a well casing when the tubing is dropped downwardly, and said body member being provided with vertical slots at diametrically opposite points thereon and alternate of said 85 slips and leaf spring members suitably mounted in said last mentioned slots and bent arcuately at their ends to permit portions thereof to project beyond the outer periphery of the body member for engagement with a well casing to prevent the rotation of said body member and parts carried thereby.

In testimony whereof I hereunto affix my signature in the presence of two witnesses. 95

WILLIAM H. McKISSICK.
